UNITED STATES PATENT OFFICE.

MYRON F. HILL, OF NEW ROCHELLE, NEW YORK, ASSIGNOR TO THE M. B. SCHENCK CO., A CORPORATION OF CONNECTICUT.

CASTER.

1,070,960.

Specification of Letters Patent. Patented Aug. 19, 1913.

Application filed August 8, 1912. Serial No. 714,009.

To all whom it may concern:

Be it known that I, MYRON F. HILL, a citizen of the United States, and resident of New Rochelle, in the county of Westchester and State of New York, have invented certain new and useful Improvements in Casters, of which the following is a specification.

My invention relates to casters which are provided with wheels, horns and pintles, and are adapted to be secured to hollow, tubular legs such as are used with metallic beds.

My invention relates particularly to a separate leg mount not secured to the caster, but adapted to be associated therewith and sold in connection with a caster of the standard type.

Legs having beadings or ornaments cast thereon or driven upon them by force and thereby frictionally secured to the legs have been commonly used in the art. Casters having beadings, or, as they are termed technically, leg mounts formed as a part of the caster have also been commonly used in the art. My invention therefore differs from these forms of casters and leg mounts by having a leg mount which is not secured thereto and may be sold with the caster but apart therefrom.

Figure 1 shows partly in vertical section one form of my invention. Fig. 2 shows an outside elevation thereof. Fig. 3 shows the same as applied to a ball or roller bearing casting. Fig. 4 shows an outside view thereof.

In Fig. 1 is shown a wheel 1 in a horn 2 which is secured to a pintle 3 adapted to be secured to the hollow metallic leg 4. Upon the pintle is secured a supporting disk 5 upon which the bottom of the leg 4 rests. The supporting disk 5 is secured to the pintle at 6 and centered upon the pintle at that point. The supporting disk and pintle are secured to the leg 4 by resilient or spring arms 7 engaging the inside of the leg at 8. These spring arms are extended upwardly from the bottom where the spring part surrounds and engages the pintle at 6 and thence passes through the apertures 9. After engaging the leg at the points 8 these arms are inclined inwardly at 10 to provide inclined faces for engaging the bottom of the leg when inserted and the upper ends of these spring arms 11 when the caster is withdrawn from the leg engage the frame 12,

which is preferably secured to the pintle, so that the pintle may revolve therein. Upon the pintle at 6 is also mounted a secondary disk which is distinguished from the supporting disk mainly by the fact that it does not support the leg, the supporting disk which supports the leg resting upon the shoulder 13. The secondary disk 14 is provided with a flange 15 which is adapted to engage the bottom of the leg mount 16 to prevent it from dropping off from the leg. The leg mount is not centered upon the non-supporting disk 5, but is centered upon the exterior of the leg 4 which it engages by a down-turned portion 17. This portion may be slotted to form downwardly extending spring arms adapted to grip the exterior of the leg and secure the leg mount thereto and center it thereon.

The supporting disk 5 is larger than the inside diameter of the leg 4 and smaller than its outside diameter. The leg mount 16 at its bottom is extended inwardly so that the hole in the bottom extends under the edge of the leg 4. This is for the purpose of preventing the leg mount from being accidentally displaced from its correct position, upwardly. It is prevented from being accidentally displaced downwardly by engaging the secondary disk 15 which should have an outside diameter larger than the hole in the bottom of the leg mount. These portions may be shaped in any suitable manner to accomplish these results. The leg mount is first applied to the leg and the caster is then inserted in the leg. In this way the leg mount is never secured to the caster, nor is it centered thereon, but is secured to the leg when mounted thereon. It may be sold separately from the caster. It may be used with any caster, but preferably with a caster that has the features just described.

In Fig. 2 is shown a side elevation of this construction. The leg 4 has surrounding it at its base the leg mount 16 and the flange 15 is adapted to prevent the leg mount from dropping off from the leg, though it is not essential that the leg mount should engage the flange 15.

In Fig. 3 is shown a modification of this construction in which the secondary disk as shown at 18 becomes one of the members of an anti-friction bearing. Between this secondary disk and the top of the horn 19 are

located balls or rolling devices 20 furnishing an anti-friction support for the leg upon the horn. The leg mount 21 is mounted upon the leg 22 by means of the downwardly turned portion 23 which may be slotted to form spring arms to frictionally and resiliently engage the exterior of the leg and to center the leg mount thereon. The bottom of the leg mount 21 has a hole in it which is sufficiently large to pass over the supporting disk 25 and sufficiently small not to pass over the bottom edge of the leg in case of any tendency to be displaced upwardly. The supporting disk 25 preferably has an outside diameter smaller than the exterior of the leg 22 and larger than the hole within it. To prevent any downward displacement of the leg mount 21 it engages the secondary disk 18. The leg mount and caster are sold separately. The leg mount is first applied to the leg and then the caster is inserted in the leg. The leg mount is never secured to the caster; but when applied thereto, is secured to the leg.

25 In Fig. 4 is shown an external view of this construction in which the leg 22 is provided with the leg mount 21 mounted above the flange 24 as shown.

What is claimed is:—

30 1. In a caster for a hollow metallic leg, in combination, a yoke, a pintle, and a leg supporting disk carrying frictional means adapted to engage varying sizes of legs, a separate secondary disk centered with respect to the pintle, having means to support a leg mount and a leg mount carrying frictional means adapted to engage said leg for securing purposes, said leg mount centered upon said leg and adapted to engage the means upon said secondary disk to prevent its being pushed off, said leg mount surrounding and concealing the bottom of said leg.

40 2. In a caster for a hollow metallic leg, in combination, a yoke, a pintle, and a leg supporting disk carrying frictional means adapted to engage varying sizes of legs, a separate secondary disk centered with respect to the pintle, having means to support a leg mount and a leg mount carrying frictional means consisting of spring arms adapted to engage the exterior of said leg for securing purposes, said leg mount centered upon said leg and adapted to engage the means upon said secondary disk to prevent its being pushed off said leg surrounding and concealing the bottom of said leg.

50 3. In a caster for a hollow metallic leg, in combination, a yoke, a pintle, and a leg supporting disk carrying frictional means adapted to engage varying sizes of legs, a separate secondary disk centered with respect to the pintle, having means to support a leg mount and a leg mount carrying frictional means consisting of spring arms adapted to engage the exterior of said leg for securing purposes, said leg mount centered upon said leg and adapted to engage the means upon said secondary disk to prevent its being pushed off said leg surrounding and concealing the bottom of said leg.

60 4. In a caster for a hollow metallic leg, in combination, a yoke, a pintle, and a leg supporting disk carrying frictional means adapted to engage varying sizes of legs, a separate secondary disk centered with respect to the pintle, having means to support a leg mount, and a leg mount carrying frictional means consisting of downwardly de-

pending spring arms adapted to engage the exterior of said leg for securing purposes said leg mount centered upon said leg and adapted to engage the means upon said secondary disk to prevent its being pushed off, said leg mount surrounding and concealing the bottom of said leg.

4. In a caster for a hollow metallic leg, in combination, a yoke, a pintle, and a leg supporting disk carrying frictional means adapted to engage varying sizes of legs, a separate secondary disk centered with respect to the pintle, having means to support a leg mount, and a leg mount carrying frictional means consisting of spring arms adapted to engage the exterior of said leg for securing purposes, said leg mount centered upon said leg and adapted to engage the means upon said secondary disk to prevent its being pushed off, said leg mount surrounding and concealing the bottom of said leg, an anti-friction rolling bearing carried by said caster engaging said secondary disk.

5. In a caster for a hollow metallic leg, in combination, a yoke, a pintle, and a leg supporting disk carrying frictional means adapted to engage varying sizes of legs, a separate secondary disk centered with respect to the pintle, having means to support a leg mount, and a leg mount carrying frictional means consisting of downwardly depending spring arms adapted to engage the exterior of said leg for securing purposes, said leg mount centered upon said leg and adapted to engage the means upon said secondary disk to prevent its being pushed off, said leg mount surrounding and concealing the bottom of said leg, an anti-friction rolling bearing carried by said caster engaging said secondary disk.

6. In a caster for a hollow metallic leg, in combination, a yoke, a pintle, and a leg supporting disk carrying frictional means adapted to engage varying sizes of legs, a separate secondary disk centered with respect to the pintle, and a leg mount carrying frictional means adapted to engage said leg for securing purposes, said leg mount having a hole in its bottom smaller than the exterior of the leg and larger than the supporting disk.

7. In a caster for a hollow metallic leg, in combination, a yoke, a pintle, and a leg supporting disk carrying frictional means adapted to engage varying sizes of legs, a separate secondary disk centered with respect to the pintle, and a leg mount carrying frictional means adapted to engage said leg for securing purposes, said leg mount having a hole in its bottom smaller than the exterior of the leg and larger than the supporting disk and smaller than the secondary disk.

8. In a caster for a hollow metallic leg, in

combination, a yoke, a pintle, and a leg supporting disk carrying frictional means adapted to engage varying sizes of legs, a separate secondary disk centered with respect to the pintle, and a leg mount carrying frictional means consisting of downwardly depending spring arms adapted to engage the exterior of said leg for securing purposes, said leg mount having a hole in its bottom smaller than the exterior of the leg and larger than the supporting disk and smaller than the secondary disk.

9. In a caster for a hollow metallic leg, in combination, a yoke, a pintle, and a leg supporting disk carrying frictional means for

engaging varying sizes of legs, a separate secondary disk centered with respect to the pintle, and a leg mount carrying frictional means adapted to engage said leg for securing purposes and carrying means to prevent its being pushed up too far on the leg, and means adapted to engage the secondary disk to prevent its being pushed off the leg downwardly.

Signed at New York city in the county of 25
New York and State of New York 1912.
